UNITED STATES PATENT OFFICE.

JAMES D. BOLTON, OF TRINIDAD, COLORADO, ASSIGNOR OF ONE-HALF TO
WILLIAM W. GRISWOLD, OF TRINIDAD, COLORADO.

CAN-OPENER.

SPECIFICATION forming part of Letters Patent No. 700,113, dated May 13, 1902.

Application filed October 24, 1901. Serial No. 79,830. (No model.)

To all whom it may concern:

Be it known that I, JAMES D. BOLTON, a citizen of the United States, residing at Trinidad, in the county of Las Animas and State of Colorado, have invented a new and useful Can-Opener, of which the following is a specification.

This invention relates to can-openers; and the object of the same is to provide a simple and effective device of this class designed for use in households, hotels, and other places and which is serviceable for quickly opening various-sized cans without injuring or soiling the hands of the operator.

15 The invention consists in the construction and arrangement of the several parts, which will be more fully hereinafter described and claimed.

In the drawings, Figure 1 is a perspective view of a can-opener embodying the features 20 of the invention and shown applied and as partially penetrating a can-top. Fig. 2 is a transverse vertical section of the top portion of a can and the improved opener, showing 25 the latter fully penetrated in relation to the can-top. Fig. 3 is a top plan view of the improved opener.

Similar numerals of reference are employed 30 to indicate corresponding parts in the several views.

The numeral 1 designates a cylindrical-shaped single-pointed cutter, preferably made of sheet-steel, with the point 2 and opposite upwardly-inclined spiral cutting edges 3 extending 35 to near the top edge of the cutter. The cutting edges 3 are located at the inner portion of the cutter, and the latter flares slightly toward the point 2, as clearly shown by Fig. 3, so as to increase the diametrical dimension of the cutter gradually toward the lower extremity or portion thereof. A flat-bar metallic handle 4 is provided and has one extremity 5 bent at an angle and securely fastened to the inner side of the upper portion 40 of the cutter, the opposite extremity 6 of the handle being reduced and terminally bent to form a hook 7, which is adapted to be used in pulling up or raising the cut portion of the can-top. The extremity 5 of the handle 4 is 45 attached to the inner portion of the cutter 1,

and by securing said extremity to the inner side of the cutter the latter is left clear for unobstructed penetration. Moreover, by applying the handle 4 in the manner set forth the cutter 1 is free for resilient action or permitted 55 to yield when performing the cutting operation therewith to avoid sticking, particularly when withdrawing the cutter, and which would necessarily result if the said cutter was of rigid construction, and to augment this 60 resilient or yielding action of the cutter it is cut through at the inner upper portion, as at 8, to provide free terminals 9, into which the cutting edges 3 have mergence. Secured to the handle 4 in a plane at right angles and 65 extending across the top edge of the cutter 1 is a guard 10, which is of considerably greater diameter than the upper portion of the cutter, and the function of this guard is to prevent 70 the cutter being pushed completely through the can-top after a full penetration has been made, as clearly shown by Fig. 2, and wherein it will be seen that the opposite extremities of the said guard bear upon the can-top at diametrically opposite points outside of the 75 portion cut therefrom.

In the operation of the device it is first disposed as shown by Fig. 1, and the point 2 is caused to penetrate the can-top by applying a downward pressure to the cutter 1. By continuing the downward pressure on the cutter the latter will be caused to sink through the top and the cutting edges 3 will sever the metal and cause an approximately circular portion of the top to be loosened, so that it can 85 be raised and the contents of the can made accessible. It will be seen that the lower diametrically larger portion of the cutter first passes through the can-top, and as the diameter of the cutter gradually decreases toward 90 the upper edge thereof the cut or released portion of the can-top will have the tendency to be drawn upwardly rather than pressed inwardly and to be pulled away from the adjacent uncut portion of the top rather than 95 jammed closer thereagainst. Furthermore, this operation of initially forming an enlarged cut will facilitate the withdrawal of the cutter 1 after the necessary penetration of the latter has ensued, and in the cutting 100

operation the upwardly-inclined spiral cutting edges 3 will serve to ease the separation of the portion of the can-top operated upon, and that portion of the can-top operated upon 5 which remains uncut, as shown by Fig. 1, may be severed by rotating the cutter. The completely-severed portion of the can-top will be drawn out with the cutter when the latter is removed, because the upper smaller 10 diametrical portion of said cutter will frictionally hold the removed part of the can-top.

The upwardly-inclined arrangement of the cutting edges 3 facilitates the easy and rapid movement of the cutter downward through 15 the top. The shape of the cutter, as set forth, also operates to stretch the opening made thereby, and said shape in conjunction with the inherent resiliency of said cutter will overcome any tendency toward an annoying 20 or disadvantageous binding or hanging action. By forming the entire device of metal a more durable structure results, and it is proposed to change the proportions and dimensions at will. It will be understood, 25 moreover, that the only point of attachment of the blade to the handle is at the center of its upper edge, thus leaving the entire blade free for transverse expansion and contraction. Therefore when the blade is forced into 30 a can-top the tendency of the severed portion of the top to spread the blade, owing to the upward reduction in diameter of the latter, will cause a frictional bearing of the inner surface of the blade against the periphery of 35 the severed portion, which will serve to lift the severed portion out of the can when the tool is raised after the completion of the cut. Moreover, the slight expansion of the blade due to the outward pressure of the severed 40 portion of the top will not carry the upper edge of the blade beyond the arms of the brace or cross-head 10, owing to the fact that these arms are extended a considerable distance beyond the normal positions of the sides of 45 the blade. Preferably the extremities of the cutting edge terminate short of each other to leave a portion of the top unsevered to form

a hinge upon which the severed portion may be folded back.

Having thus described the invention, what 50 is claimed as new is—

1. A can-opener having an approximately cylindrical upwardly-tapered or reduced blade provided with cutting edges which progress spirally in opposite directions from a 55 penetrating-point, to cause the transverse compression of the severed portion of a can-top as the blade advances therethrough.

2. A can-opener having an approximately cylindrical, transversely-expansible blade, 60 reduced in diameter toward its top, and having spirally-disposed downwardly-convergent cutting edges intersecting to form a penetrating-point.

3. A can-opener having an approximately 65 cylindrical, transversely-expansible blade provided with spirally-disposed downwardly-convergent cutting edges intersecting to form a penetrating-point, and a handle secured to the upper edge of the blade at one point and 70 provided with a brace having a plurality of bearings on the edge of the blade to provide for the application of downward pressure to the blade without interfering with transverse expansion.

4. A can-opener having an approximately cylindrical, transversely-expansible, upwardly-reduced or tapered blade, of which the cutting edges progress spirally from a 80 penetrating-point and terminate short of each other near the upper edge of the blade, and a handle secured to the blade at its upper edge and remote from the terminals of the cutting edges and provided with a brace or cross-head bearing on the upper edge of the 85 blade adjacent to said terminals of the cutting edges.

In testimony that I claim the foregoing as my own I have hereto affixed my signature in the presence of two witnesses.

JAMES D. BOLTON.
